Primary Examiner — Robin V Webster(74) *Attorney, Agent, or Firm* — Wells St. John, P.S.(57) **CLAIM**

I claim the ornamental design for a showerhead, as shown and described.

DESCRIPTION

FIG. 1 is a bottom, right, front perspective view of an ornamental design for a showerhead;

FIG. 2 is a top, left, rear perspective view of an ornamental design for a showerhead of FIG. 1;

FIG. 3 is a front elevational view of the ornamental design shown in FIG. 1;

FIG. 4 is a left elevational view of the ornamental design shown in FIG. 1, the right elevational view being a mirror image of the view shown;

FIG. 5 is a back elevational view of the ornamental design shown in FIG. 1;

FIG. 6 is a top plan view of the ornamental design shown in FIG. 1; and,

FIG. 7 is a bottom plan view of the ornamental design shown in FIG. 1.

The dashed lines illustrate environment that does not form a part of the present invention, and no claim is made to the material illustrated with dashed lines.
